Specification for Design.

Patented Dec. 20, 1921.

Application filed March 8, 1920. Serial No. 450,636. Term of patent 14 years.

To all whom it may concern:

Be it known that I, FREDERICK WILLSON, a citizen of the United States, residing at Reading, in the county of Berks and State of Pennsylvania, have invented a certain new, original, and ornamental Design for a Respirator Filter-Ring, of which the following is a specification, reference being had to the accompanying drawing, forming part thereof.

Figure 1 is a front view of a respirator filter ring showing my new design.

Fig. 2 is an edge view of the same.

I claim:

The ornamental design for a respirator filter ring, as shown.

In testimony whereof I affix my signature.

FREDERICK WILLSON.
